US00D931233S

(12) **United States Design Patent** (10) **Patent No.:** **US D931,233 S**
Pan (45) **Date of Patent:** **** Sep. 21, 2021**

(54) **PRESSURE SWITCH**

(71) Applicant: **SHENZHEN FEIYACHI INDUSTRIAL CO., LTD.**, Shenzhen (CN)

(72) Inventor: **Bilan Pan**, Shenzhen (CN)

(**) Term: **15 Years**

(21) Appl. No.: **29/759,555**

(22) Filed: **Nov. 24, 2020**

(30) **Foreign Application Priority Data**

Nov. 4, 2020 (CN) 202030665218.5

(51) **LOC (13) Cl.** **13-03**

(52) **U.S. Cl.**

USPC **D13/158**; D13/171; D22/108

(57) **CLAIM**

The ornamental design for a pressure switch, as shown and described.

DESCRIPTION

FIG. 1 is a perspective view of a pressure switch showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the pressure switch where the pressure switch is in a first configuration of use;

FIG. 10 is another perspective view of the pressure switch where the pressure switch is in a second configuration of use; and,

FIG. 11 is an enlarged view of portion 11 shown in FIG. 1. The broken lines in the drawings depict portions of the pressure switch that form no part of the claimed design.

1 Claim, 11 Drawing Sheets
